UNITED STATES PATENT OFFICE.

AUGUSTINE C. WEST, OF BOSTON, MASSACHUSETTS.

DESIGN FOR AN OIL OR GAS HEATER STAND.

SPECIFICATION forming part of Design No. 23,593, dated June 19, 1894.

Application filed April 23, 1894. Serial No. 508,736. Term of patent 7 years.

To all whom it may concern:

- Be it known that I, AUGUSTINE C. WEST, a citizen of the United States, residing at Boston, county of Suffolk, State of Massachusetts, 5 have invented and produced a new and original Design for an Oil or Gas Heater Stand, of which the following is a specification, reference being had to the accompanying drawing, showing the same.
- 10 The features of my design are embodied in the general configuration of the heater-stand, which comprises an inverted disk-shaped base, a cylindrical body which caps the heater, and the upright posts which are arranged 15 about said body.
- Specifically my design comprises a circular base 2 of inverted disk-shaped form having an outwardly flaring rim 3 with a fluted or scalloped edge and with rectangular openings 20 4 arranged in two concentric circles. The top of the base is a plain flat surface. Rising from the base appear three straight posts 6 which terminate in molded knobs 7, while just beneath the said knobs is an annular 25 band or ring 8 rectangular in cross section.
- Girdled or inclosed by said ring 8 and midway of its length is a cylindrical body 9 which serves as the cap for the heater-stand. The body portion of this cap is a plain surface with two parallel rows of moldings 10, while 30 at the top are a number of quarterfoil shaped openings 12 joined in pairs. The upper end of this cap is closed by a cover 13, which is a circular disk with edges projecting over the cap and with a central oval prominence 14 35 having convergent oblong openings. Upon the cover is a handle 15 which appears, as a spirally-wound wire about a central rod, the diameter of the spirals tapering toward each end from the center. 40

What I claim is—

The design for an oil, or gas heater-stand, substantially as described and shown.

In witness whereof I affix my signature in presence of two witnesses.

AUGUSTINE C. WEST.
